UNITED STATES PATENT OFFICE

2,595,317

SPRAY GUN

Roby Byron White, Jr., United States Navy

Application May 6, 1946, Serial No. 667,549

1 Claim. (Cl. 299—95)

(Granted under the act of March 3, 1883, as
amended April 30, 1928; 370 O. G. 757)

1

This invention relates in general to spraying apparatus and in particular to a spray gun for paint or the like.

An object of this invention is to provide a spraying device that is adapted to operate from a portable reservoir of compressed gas.

Another object is to provide a spray gun that operates from a small container of a compressed gas or the like.

An additional object is to provide a spray gun adapted to utilize as a source of compressed gas a cylinder of carbon dioxide, nitrogen, neon or the like.

Further objects and advantages of this invention, as well as its construction, arrangement and operation will be apparent from the following description and claims in connection with the accompanying drawings, in which

Fig. 1 is a side elevation in cross section of a spray gun showing a preferred embodiment of this invention, and

Fig. 2 is a side elevation in cross section showing another embodiment thereof.

Fig. 1 shows a spray gun generally designated 10 and including a reservoir 11 secured removably to a head or connector 12 on which is mounted a removable handle 13 containing a gas reservoir 14.

The gas reservoir 14 comprises a container of compressed, liquefied, or solidified gas, such as a small cylinder of highly compressed carbon-dioxide. In the preferred form of the invention, the cylinder is so arranged that the compressed gas contained therein is made available for use by puncturing the top of the cylinder.

The handle 13 is adapted to fit on the head and connector 12 by means of a threaded connection 15. The handle is hollow, having a recess 16 adapted to receive and retain the gas reservoir 14 and to hold the reservoir 14 in such a position that the top 17 of the reservoir is almost flush with the top of the handle. Optionally, the handle is shaped so as to fit comfortably within the hand of the operator and is designed with a finger grip or other structure conventional in tool handles and the like.

The head 12 has two studs 18 and 19 extending at an angle thereto, one at each end thereof. Stud 18 has one extremity threaded or otherwise fitted to receive handle 13. Stud 19 preferably has a portion threaded internally at its end to receive reservoir 11 thereon. A channel or tube 20 passes through head 12, opening at one end on the surface of stud 18 distal head 12 and opening at the other end in stud 19 so as to terminate within reservoir 11. Tube 20 is curved toward one end to by-pass a valve arrangement, herein-after described, contained in head 19. Suitable packing 48 provides substantially tight connections between various parts of the sprayer 10.

2

Mounted on the lower side of stud 18 at the end of tube 20 is a sharp, hollow needle 21, which is positioned and adapted to feed into tube 20. This needle is mounted on stud 18, for example by means of washer 22, and optionally can be countersunk partially within stud 18. The lower or pointed end of needle 21 is adapted to engage and enter the top 17 of reservoir 14.

When reservoir 14 is placed within handle 13 and the handle is screwed on to the stud 18, needle 21 punctures the top 17 of reservoir 14, thereby opening the seal of the reservoir and making the gas contained therein available for use. Passing through stud 19 and exiting from the front end 15 of head 12 is a channel 23, which is adapted to carry a liquid from reservoir 11 to a nozzle 24. Nozzle 24, positioned at the exit point of channel 23 in an enlarged chamber 29 at the end thereof, is a conventionally designed nozzle preferably adapted to be screwed into the open end of chamber 29. A second channel 25 likewise leads from reservoir 11 to nozzle 24, joining chamber 29 somewhat before the position of the nozzle. A valve arrangement, hereinafter described, controls the flow of gas or liquid through channels 25 and 23.

Positioned on stud 19 and adapted to feed into channel 23 is a tube 26, which extends to a point near the bottom of reservoir 11 and is open thereto to permit entrance of the liquid, paint or the like stored in reservoir 11. This tube 26 optionally is threaded and thus mounted removably on stud 19. At the open end of tube 26 a filtering screen 27 or similar device may be provided to prevent entrance of dirt and other impurities into the tube and consequently to protect nozzle 24 from clogging.

Optionally, an auxiliary channel 28 leads from bore 31 to chamber 29 for the purposes of aiding in directing the flow from reservoir 11 in a more satisfactory manner, producing a fine spray and providing an escape channel for liquid or paint trapped at the point of needle 30.

Fig. 1 shows one valve arrangement for controlling the flow from reservoir 11 through nozzle 24. This valve arrangement comprises a needle 30 adapted to be moved within tube or bore 31, and to shut off channels 23 and 25. When needle 30 is inserted fully within bore 31, channels 23 and 25 are closed off completely, preventing flow of liquid or gas therefrom, and when needle 30 is withdrawn partly from bore 31, channel 23 is opened to permit free passage of liquid therethrough. In addition, a notch or passage 32 on needle 30 is a portion of reduced cross-section so positioned that it is aligned with channel 25 when needle 30 is almost but not fully inserted into bore 31. A spring 33 is mounted in an enlarged recess 34 at the open end of bore 31 and positioned therein by means of nut 35, whereby needle 30 is urged constantly in a direction to close off.

channels 23 and 25. Needle 30 extends through nut 35 outside of stud 19, and the end of said needle is secured pivotally to a trigger handle 36, which in turn is mounted rotatably on head 12. Thus, as trigger handle 36 is pulled back, needle 30 is likewise pulled back against the urging of spring 33 to open channels 23 and 25.

As can be seen from Fig. 1, when trigger 36 is pulled back slowly, notch 32 is first aligned with channel 25, thus permitting some gas in the reservoir to escape from channel 25 and nozzle 24 and thus cleaning out the nozzle 24. As trigger 36 is pulled further back, channel 25 is closed and needle 30 opens channels 23 and 28, permitting the free passage of liquid through nozzle 24. Subsequently, when trigger 36 is released, channel 23 is first closed and then notch 32 is aligned with channel 25 to permit bleeding off of some residual gas pressure, thereby serving to clean out nozzle 24 and channels 23 and 25. Optionally, a plug 38 is positioned at the rear of head 12 and adapted to be screwed into the head to close off channel 20 between reservoirs 14 and 11. Bleeding of all the residual gas pressure through notch 32 after spraying is completed permits complete release of the gas pressure for subsequent disassembly of the gun.

In Fig. 2 there is shown another form of valve arrangement and spray adjustment.

A valve stem 40 is mounted in a bore 31a in an arrangement similar to the mounting of valve needle 30 in Fig. 1. The position of valve stem 40 is controlled by spring 33 and plug 35 in a manner similar to that shown in Fig. 1. Mounted on valve stem 40 is a guide 41 that divides bore 31a between channel 23a and channel 25a, guiding stem 40. Said guide 41 is oval in cross-section, permitting passage of gas about bore 31 to clean out channel 23a and nozzle 24a. A valve-trip 42 mounted on stem 40 is adapted to coact with a valve 43 positioned in channel 25a adjacent to valve stem 40, so that valve 43 can be opened to permit the escape of gas through channel 25a. A second valve-trip 44, oval in cross-section, is positioned at the inner end of valve stem 40 and is adapted to open valve 45, which is similarly positioned in tube 23a. Thus, when trigger 36 is pulled back, valve-trip 42 first opens valve 43 and permits an escape of gas, which serves to clear out nozzle 24. As trigger 36 is pulled further back, valve-trip 44 opens valve 45, thus ejecting liquid through nozzle 24a. As the trigger is released, the flow of liquid through valve 45 is cut off, and subsequently valve-trip 42 opens valve 43, permitting the bleeding off of excess gas pressure for cleaning of nozzle 24a. Springs 43a and 45a hold valves 43 and 45 normally in a closed position.

A thumb screw adjustment 46 controls an adjusting member 47 adapted to vary the character of the ejected spray.

In the form of the invention shown in Fig. 2, the results accomplished are similar to the results obtained by the form shown in Fig. 1, with the difference that a valve and valve-trip combination is used to control the flow of gas and liquid instead of a needle-valve arrangement as shown in Fig. 1.

It is understood, of course, that reservoir 14 can be an integral part of handle 13, whereby the entire handle and reservoir is replaceable.

The spray apparatus described herein is adapted for use with a small portable reservoir of compressed gas, and accordingly is sufficient within itself and does not need an external power source

or the like. The choice of the compressed gas obviously will depend on the nature of the spray. For example, in paint spraying where paint to be used is not substantially a solvent for carbon dioxide, it is understood that the most convenient gas reservoir will be a small cylinder of carbon dioxide. However, where carbon-dioxide gas is substantially soluble in the paint, it will be necessary to use another gas such as compressed air, nitrogen, neon or the like.

The spraying apparatus described herein is particularly adapted for use in connection with a dissolved-type paint such as lacquer or the like, or in connection with a sediment-type paint wherein the particles are sufficiently small so as not to clog the nozzle or valve arrangement.

It is further understood that numerous variations in the structure and operation of the spraying apparatus can be made without departing from the scope of the invention. For example, there has been shown a plug (refer to plug 38 in Figs. 1 and 2) adapted to shut off the flow of compressed air from reservoir 14. It is obvious that this plug type of control can be replaced by an automatic control operated directly from trigger 36.

The invention described herein may be manufactured and used by or for the Government of the United States of America for governmental purposes without the payment of any royalties thereon or therefor.

I claim:

A sprayer comprising a head, a spray nozzle, liquid reservoir and compressed-gas reservoir mounted in said head, means to feed gas from said gas reservoir to said liquid reservoir, a tube communicating between the nether portion of said liquid reservoir and said nozzle through a passageway in said head, a channel communicating between said liquid reservoir and said nozzle, a bore in said head intersecting said passageway and said channel, and a spring-loaded, trigger-actuated element mounted slidably in said bore to seal said passageway and said channel, said element having a portion of reduced cross-section positioned to be aligned with said channel when said element is withdrawn partly from said bore and to be out of such alignment when said element is withdrawn further from said bore to permit passage of liquid through said tube, and a second channel communicating between said nozzle and the end of said bore proximate said nozzle.
